UNITED STATES PATENT OFFICE.

AUSTEN M. CURTIS, OF BROOKLYN, NEW YORK, ASSIGNOR, BY MESNE ASSIGNMENTS,
TO WESTERN ELECTRIC COMPANY, INCORPORATED, A CORPORATION OF NEW YORK.

PROTECTOR FOR ELECTRIC CIRCUITS.

1,325,889.

Specification of Letters Patent. Patented Dec. 23, 1919.

Application filed November 1, 1915. Serial No. 59,055.

To all whom it may concern:

Be it known that I, AUSTEN MANSFIELD CURTIS, a citizen of the United States, residing at Brooklyn, in the county of Kings 5 and State of New York, have invented certain new and useful Improvements in Protectors for Electric Circuits, of which the following is a full, clear, concise, and exact description.

10 This invention relates to a protecting device for electric circuits. Its object is to protect an electric circuit against high impressed voltages by diverting a portion of the power supplied by the source of impressed voltage around the receiving circuit, the ratio of this diverted power to the power consumed in the said circuit being greater 15 the higher the impressed voltage. This object is accomplished by actually or effect- 20 tively shunting the electric circuit to be protected by an electrical conductor which has the property that its resistance decreases with increasing applied voltage. Under these circumstances, as the voltage impressed 25 across the terminals of the electric circuit and the protecting device is increased, the ratio of current in the protecting conductor to that in the protected circuit will increase.

30 Protection of this kind is particularly desirable in signaling systems, for example in wire or wireless telegraph or telephone systems in which the receiving device is often subjected to impulses of comparatively high voltage, the effect of which is to deafen the 35 operator and consequently to render the signals following the disturbing impulse unintelligible.

30 The nature of this invention will be more fully explained in connection with the drawings, in which Figure 1 represents the simplest embodiment of this invention; Fig. 2 represents a slightly different form in which it is possible to send a continuous current through the protecting conductor; Fig. 3 45 shows a form in which it is possible to adjust the effective resistance of the protecting conductor with respect to that of the receiving circuit to secure maximum effect. In all these figures corresponding parts are 50 denoted by like reference numbers.

Referring to Fig. 1, 1 represents a generator or other source of voltage which is to be impressed upon the receiving device 2, which latter may be, for example, an ordinary telephone receiver. 3 is the protecting

conductor and consists of a block of substance whose resistance decreases with increase of applied voltage, contact being made with this block by means of metallic plates. Connections from these metallic 60 plates or electrodes serve to connect the device in shunt to the receiving instrument 2. It has been found that many materials, notably carborundum and the oxides or silicides of certain substances, possess this property. 65 Some crystalline substances also behave in this manner. It will be obvious that if the resistance of the receiving device 2 remains constant with increasing impressed voltage, and if the resistance of the cell 3 decreases 70 with increasing voltage, the result will be that for high voltages a very much larger part of the total current delivered by the generator will flow through the cell 3 than through the receiving instrument 2. On the 75 other hand, for low voltages the cell 3 may be so constructed as to divert only a small fraction of the available power from the receiver.

Referring to Fig. 2, a system is shown 80 which is adapted for receiving alternating currents from the generator 1. It is also so arranged that continuous current may, if desired, be superposed upon the alternating current flowing through cell 3. It has been 85 found that in some cases this superposition of continuous current improves the operation of the device. In this figure, 4 is a transformer by means of which the receiving apparatus is connected to the line, 6 is a 90 battery which supplies the continuous current just mentioned, and 5 is a condenser which may be inserted if desired to prevent the flow of continuous current in the receiving apparatus 2.

Referring to Fig. 3, an arrangement is shown in which the protecting cell may be supplied with continuous current as before, and in which also the effective resistance shunting the receiving device may be adjusted to any desired value. In this figure the protecting cell is not shunted directly across the receiving instrument but is connected in circuit with the secondary of the transformer 4 whose primary shunts the receiver 2. Since it is well known that the apparent resistance introduced into the primary of a transformer, due to a resistance in its secondary, is found from the secondary resistance by multiplying it by 105 110

the square of the ratio of turns on the transformer, it will be seen that the effective shunting resistance may be made to have any desired value by adjusting the ratio of 5 turns on the transformer.

In this arrangement or in that of Fig. 2, the battery 6 may be omitted if the use of a polarizing direct current is not required.

It will be obvious that many other methods may be used for effectively inserting 10 such a protecting cell in shunt with a receiving device without departing from the spirit of this invention.

What is claimed is:

15 1. The combination of a line, a telephone receiver therefor, a protecting device for said receiver, said device comprising a resistance which decreases with increasing applied voltages, and means for supplying a 20 polarizing potential to said device.

25 2. The combination of means to be protected from excessive voltages, a protective device therefor, comprising resistance which decreases with increasing applied voltages, a source of current for said 30 means, and means for polarizing said device.

35 3. The combination of means to be protected from excessive voltages, a protective device in shunt thereto, comprising resistance which decreases with increasing applied voltages, a source of current for said 40 means, and means for polarizing said device.

45 4. The combination of a line, means for supplying to said line impulses to be transmitted, a protective device for said line comprising carborundum, and a polarizing source of current for said carborundum.

50 5. A protective system comprising a telephone receiver, a protective device comprising a carborundum by-path for said receiver, means comprising a source of voltage for supplying current to said carborundum, and means for preventing flow of current 55 from said source to said receiver.

6. A protective system comprising a line

subject to an electrical disturbance, means to be protected associated with said line, and a protective device comprising resistance which decreases with increasing applied voltages, said device being inductively 50 coupled to said line.

7. A protective system comprising a line, a telephone receiver therefor, a protective device comprising carborundum in shunt 55 to said receiver and inductively coupled to said line, and a source of current for polarizing said carborundum.

8. A protective system comprising a line, a telephone receiver therefor, and carborundum connected in shunt to the sides of said 60 line through a low impedance path.

9. A protective system comprising a line, a telephone receiver therefor, and carborundum connected in shunt to said receiver 65 through a low impedance path.

10. The combination of means to be protected from excessive voltages, a protective by-path therefor comprising resistance which decreases with increasing applied voltages, a source of current for said 70 means, and means for polarizing said resistance.

11. A protective system comprising a line, a telephone receiver therefor, a protective 75 device comprising carborundum in circuit with said receiver and inductively coupled to said line, and a source of current for polarizing said carborundum.

12. A protective system comprising a line, 80 a telephone receiver therefor, and a low impedance by-path comprising carborundum in circuit with said receiver.

13. A signaling system comprising a line, a telephone receiver therefor, and a negative 85 resistance by-path connected in shunt to said receiver for preventing a tone of supernormal intensity in said receiver.

In witness whereof, I hereunto subscribe my name this fourth day of October A. D., 90 1915.

AUSTEN M. CURTIS.

It is hereby certified that in Letters Patent No. 1,325,889, granted December 23, 1919, upon the application of Austen M. Curtis, of Brooklyn, New York, for an improvement in "Protectors for Electric Circuits," errors appear in the printed specification requiring correction as follows: Page 2, claims 8, 9, and 12, lines 59, 63, and 80, for the word "protective" read *telephone*; and that the said Letters Patent should be read with these corrections therein that the same may conform to the record of the case in the Patent Office.

Signed and sealed this 14th day of December, A. D., 1920.

[SEAL.]

L. B. MANN,

Acting Commissioner of Patents.

Cl. 175—30.
